SAMPLING DEVICE

Robert M. Levy, Brevard, N. C., assignor to Ecusta
Paper Corporation, a corporation of Delaware

Application December 7, 1945, Serial No. 633,546

6 Claims. (Cl. 73—421)

1

This invention relates to sampling devices and more particularly to a device that is adapted for obtaining samples from a bale or compact mass of fibrous material of substantial thickness. This is a continuation-in-part of my co-pending application Serial No. 466,524, allowed June 8, 1945, which was abandoned following transfer of its subject matter to the present application.

For the purpose of determining the average physical and chemical characteristics of fibrous material stored or shipped in bales, it is essential to obtain a sample that will represent or approximate the mean or average material in the bale. This is difficult to accomplish where the bale is of relatively great thickness or length since this requires penetrating a substantial distance into the bale to obtain a representative sample.

In my investigation of this problem, I have found that the ordinary, portable, hand operated sampling devices used generally for sampling hard or more or less solid materials, will not work satisfactorily. If such a device is used to obtain a sample from a bale of fiber it requires very great pressure to effect deep penetration of the bale. This portable type of device, I have found, cannot be operated satisfactorily by one man and in fact the desired type of sample cannot be obtained even when the sampling device is applied with the combined strength of several men.

Regarding the power operated sampling devices, I am not aware of any prior device that is suitable for obtaining a representative sample from a bale or compact mass of tough fibrous material, as obtained by the device of my invention.

The sampling device of my invention overcomes the major defects and limitations of the prior devices mentioned above. It operates with relatively high pressures and has a long stroke or cutting length by virtue of the fact that the cutting tool and rotating means are mounted on a moveable carriage. With this type of arrangement the cutting tool can be progressively presented while it is rotating to the bale of fibrous material, and will thereby penetrate through the substantial depth or length of the bale being sampled. The core sample obtained in this manner is more truly representative of the average characteristics of the material in the bale than a sample obtained from the surface of the bale or

even by penetrating the bale for a short depth. By virtue of this improvement it is not necessary to select and analyze a large number of samples, as has been the practice in prior times, to obtain a true evaluation of the sampled material.

I have found that the type of drill or cutting tool used in the sampling device is very important and that the usual corkscrew and drill forms of cutters will not work satisfactorily. In the sampling device which I have developed I use an elongated tube having a circular knife edge formed at the end for cutting into the fibrous material and obtaining an elongated sample core of the material. This core is forced into the tube during the cutting operation and subsequently may be removed therefrom by a core ejecting means which is associated as an element of my sampling device.

20 In the operation of my device it is advantageous to use a metal core taking tube of relatively thin but strong wall construction and so designed that the core sample of fibrous material will have a diameter approximately the same as the inside diameter of the cutting tube. If the sample has a greater diameter than this, it will tend to clog the tube and prevent smooth and efficient operation. It is also desirable to make the cutting end of the tube of hardened steel to prevent wear and breakage, and to weld this tip or cutting end to the remaining length of the tube, which may be of any suitable metal. Also, instead of metal, I may use any other suitable material that will withstand the stresses involved in the cutting operation and will not wear out too quickly. For example, a hard synthetic resin tube with a suitable cutting end might be used.

40 The knife edge or actual cutting end of the tube which I use may be either smooth surfaced or serrated. Also, where desired, the tip or cutting end of the tool may be an integral part of the tube if the tube material used is of sufficient hardness and strength to form and maintain a sharp cutting edge.

45 The device of my invention is described herein with special reference to the sampling of fibrous materials, such as, for example, straws or bast fibers or mixtures of bast fibers and woody materials. However, the device may also be used

for the sampling of other materials, such as, for example, fertilizers, earth, etc.

The details of construction and mode of operation of my sampling device will be more fully understood from the following description taken in conjunction with the accompanying drawing in which:

Fig. 1 is a side view of one embodiment of a sampling device constructed according to the present invention;

Fig. 2 is a corresponding front view;

Fig. 3 is a corresponding top or plan view;

Figs. 4 and 5 are detail views of the cutting end of the core taking tube shown in the preceding figures;

Fig. 6 is a side view of a modified form of the sampling device of the present invention;

Figs. 7 and 8 are corresponding top and rear end views, respectively;

Fig. 9 is a detail of the associated core ejecting means.

Fig. 10 is a sectional detail of the core taking tube;

Fig. 11 is a further detail of the driving connection for the core taking tube;

Fig. 12 is a view in perspective illustrating the type of sample obtained with my device; and

Figs. 13 and 14 are more or less diagrammatic illustrations of the manner in which the sampling device shown in Fig. 6 and following is presented for sampling operations.

Referring now to the drawing, the embodiment of my sampling device illustrated in Figs. 1 to 5, inclusive, comprises generally a base 10 and a vertically moveable carriage 11 on which a motor 12 is mounted, the carriage 11 being counter-balanced by a weight 13. The core taking tube in the form of an elongated thin wall metal tube is shown at 14, and the core ejecting mechanism is indicated at 15. Means for holding the bale or other material to be sampled include an adjustable support or clamp 16 and an opposing clamp 17, which is adjustable by a means indicated at 18 for varying the distance between the clamps 16 and 17. The clamp 17 may be locked in a desired position by means of the locking device indicated at 19.

The carriage 11 is moveable upward and downward by means of the rack 20 and pinion 21, the latter being rotatable by a spoked wheel 22. The weight 13, which is connected to the carriage 11 through the intermediary of a pulley 23 and cable 24, is sufficient to hold the carriage 11 in any selected location. During operation the carriage 11 and accordingly the cutting tool 14 are moveable vertically, upward and downward, by rotating the spoked wheel 22 which causes vertical displacement between the pinion or spur gear 21 and the rack 20.

As the rotating tube 14 penetrates the bale, a core of the sampled material progressively rises in the tube. When the full stroke of the cutting tube has entered the bale, the tube is raised by upward movement of the carriage 11. The sample core is ejected from the tube by means of the ejecting device generally indicated at 15. This device comprises a metal rod formed into an inverted U-shape and having hand grasp extensions 25 at its ends, and a centrally located plunger 26.

When the core ejecting device is not in operation it is maintained in elevated position by means of an upright member 27 that is attached to a supporting and guiding arm 28. For ejecting cores the device 15 is lifted upward and slightly.

rotated to free itself from the member 27 which is forked at its extending end as indicated at 27A. When it is then lowered the central ram rod 26 progressively enters the tube 14 and pushes the sample of material out of the lower end of the tube. The fibrous sample obtained generally the shape and size of the cutting tube 14 (see Fig. 12) but is rather easily broken up into shorter sections if desired in connection with investigations carried out on the sample.

As hereinbefore stated, the cutting end portion of the core taking tube 14 may be a separate piece. A practical example of this is shown in Fig. 4, wherein a cutter head 29 is welded to the tube, as at 30. This particular head, as shown, has a plain circular, sharpened, cutting edge 31 that is coincident with the cylindrical inner wall face of the head, which face is in turn flush with the bore face of the tube. The lower outer face of the head 29 is conical, i. e., it tapers to the cutting edge from a cylindrical, circumferential, protuberance 32 of slightly greater diameter than the outside diameter of the tube. Above the protuberance 32 the circumference of the head 29 tapers down to the surface of the tube.

For some materials the edge of the cutting end of the tube 14 may be serrated as at 33 (see Fig. 5), and the end portion 34, corresponding to the aforesaid head 29, may be formed integral with the tube as shown. In some cases the cutting edge of this integral structure may be plain and unbroken as with the separate head 29 shown in Fig. 4. So, too, the edge of the head 29 may be serrated if so desired. But, in any case, the entire bore of the tube, including the cutting end portions, should be smooth and uninterrupted by internal protuberance of any kind. It is advantageous to provide the external annular protuberance 32 adjacent the cutting edges. By this provision the hole in the bale being sampled is expanded slightly behind the cutting edge as the tube progressively penetrates the bale. This appreciably minimizes friction between the outer face of the tube and the hole that is bored in the bale, inasmuch as the material remaining in the bale next adjacent the bore from which the sample core is taken, is usually of comparatively slow recovery after such expansion. For sampling some materials the external bulge 32 may not be advantageous, and a straight wall tube and cutter head will then be used.

For portability the base 10 of the sampling device is mounted on casters, a pair 35 of which are rigidly located, one each on opposite sides, at one end of a rectangular platform frame 36. At the opposite end of this frame is a triangular extension 37 supported at its apex on a swiveled caster 38.

An oblong platform plate 39 is adjustably mounted at its ends on the side members of the frame 36 which are slotted, as at 40. These slots receive bolts 41 that are inserted upwardly therethrough, and through apertures provided therefor in the plate 39. The bolts are provided with nuts 42 that are tightened against the plate 39 so as to secure it in its adjusted position on the base frame.

The bale clamp 16, as shown, comprises a vertical channel member 43 having at its lower end an angle-footing 44 that rests slidably on the platform plate 39. Midway of its ends, the clamp member 16 has one end of an adjusting and backing screw 45 swiveled thereto. The screw 45 works through a bearing 46 on an upright, angle-section support 47 and is provided at its outer end 75 with a spoked wheel 48. By turning the wheel 48

in either direction the bale clamp 16 is moved inward or outward to locate bales of different sizes on the platform plate 39.

The opposite bale clamp 17 comprises a channel member 49 similar to the channel member 43 of the clamp 16, and it is provided with a footing 50 similar to and functioning in the same manner as the footing 44 of said member 43. Both channel members 43 and 49 have their side flanges disposed inwardly of the device so as to engage directly the opposite sides of a bale placed between them. Thus, the flanges of the members 43 and 49 indent the sides of the bale when said members are pressed thereagainst in clamping effect.

Pinned at one end to the clamp member 49, as at 51, is a preferably tubular, push-and-pull bar 52. This bar is slideable through a horizontal guide sleeve 53 that is located between and welded or otherwise rigidly secured to a spaced pair of vertical, angle-section, supports 54 that are provided with a stout, rigid, footing 55 welded or otherwise fastened with stable support on the platform plate 39. The sleeve 53 is split longitudinally, as at 56, and is formed with apertured lugs 57 on opposite sides of the slit. The aperture of one of these lugs is screw-threaded to receive the correspondingly threaded end portion of a shouldered clamping screw 58 whose reduced portion adjacent the screw-threaded portion works freely, both rotatably and longitudinally, in the aperture of the opposed lug, with its shoulder engaging the same lug. Thus, by turning the screw 58, the split portion of the sleeve 53 is either loosened or tightened and the bar 52 accordingly either made free to move in the sleeve or tightly secured against movement. A suitable handle or operating lever 59 is provided on the screw element for convenient manipulation thereof.

For forcibly operating the clamp element 49 the push-and-pull bar 52 is provided on opposite sides with a pair of link members 60 that pivotally connect it with the bifurcated portions 61 of an operating lever 62. The forks 61 of the lever 62 are pivotally mounted, as at 63, on bracket arms 64 that are welded or otherwise rigidly secured to the pair of uprights 54. Thus, with a bale placed on the platform plate 39, and the clamping element 16 adjusted against one side of the bale, the other clamping element 17 is readily movable into clamping contact with the opposite side of the bale by the hand of a single operator. The operator has only to first manipulate the lever 59 with one hand (usually the left) to loosen the push-and-pull bar 52. Then, with his other hand operate the lever 62 to force the bar 52 inward until the clamping element 17 is pressed against the bale. After the bale is thus clamped and the bar 52 again locked by reverse actuation of the lever 59, the same operator is then free to operate the core sampling means of the apparatus through the instrumentalities hereinbefore described.

In the construction and arrangement illustrated in Figs. 1 to 5, inclusive, of the drawing, the core taking and ejecting means, hereinbefore generally described, is carried on a single, tubular, main supporting column 65 supportedly secured itself, at its lower end, in a socket element 66 that is in turn solidly supported on a pair of cross members 67 of the base frame 36 comprising part of the portable base 10.

The column 65 is braced on the base 10 by inclined lateral stays 68 of angle-section and a pair of longitudinal stays 69. It not only supports and guides the carriage 11 but also houses the counter-balancing weight 13. The weight

cable pulley 23 and the ejector-carrying arm 28 are also mounted on the upper end portion of the column.

The carriage 11, as shown, comprises opposed upper and lower arms 70. These arms have base-end portions 71 bored to fit slidably and are guided in longitudinal movement, without rotation, on the column 65 by an elongated spline 72 fixed on the column (see Fig. 1). The base portions 71 are rigidly connected and held spaced apart by an angle-section strut member 73 at one side of the column and at the opposite side by a flat strut member 74. The end of the weight cable 24 is connected, as at 75, to the upper end portion of the strut member 74 (see Fig. 1).

The strut member 74 has the conventionally shown, hereinbefore described, motor 12 mounted thereon, as at 76. On the motor shaft is a driving pulley 77, belted, as at 78, to a driven pulley 79 fixed on a tubular vertical spindle 80 that is journaled in suitable rotary and end-thrust bearings, shown conventionally at the outer end portions 81 of the carriage arms 70 (see Fig. 1). The upper end portion of the tubular cutting and sample-core-taking tube 14 is secured in the spindle 80 by suitable collets 82 (conventionally shown). The tube 14, of course, extends some distance below the carriage 11 and is of a length sufficient to penetrate substantially the full vertical thickness of the largest size bale to be sampled on the platform plate at the base of the apparatus. Accordingly, the carriage 11 is liftable to a height on the column 65 so that the bottom end of the tool 14 can clear the top of a positioned bale of maximum vertical dimension. The ejector rod or plunger 26 is made proportionately long enough to traverse the entire length of the tube 14 so as to completely extrude the sample core taken therein.

In the presently described structure, the rack 20, by which the carriage 11 is raised and lowered, has its upper end portion secured to the extended lower end portion of the strut member 74, as at 83. The lower portion of the rack is guided in its longitudinal travel through a bracket 84, a portion of which is looped around the column 65 and bolted as at 85 or otherwise secured in place. This bracket 84 also supports the pinion 21 which is in engagement with and actuates the rack. A shaft 86 that rotates the pinion 21 and carries the spoked operating wheel 22 is supported in a bearing 87 on an upright, angle-section, member or post 88. This member 88 is secured at its lower end to one side of the base 10, and it is braced by a diagonal stay 89. As shown, the stay 89 inclines from its upper portion that is attached to the member 88, across the device, and is fastened at its lower end to the opposite side of the base 10.

The modified form of the sampling device of the present invention illustrated in Fig. 6 and following of the drawing, differs from the embodiment just described in that it is arranged with a horizontally disposed core taking tube 90 and adapted so that the core taking tube may be readily presented in opposed position to a bale of fibrous material for a sample taking operation.

The core taking tube 90 is disposed in this manner on a supporting frame structure comprising bottom side members 91 which are formed to converge rearwardly, as shown, and cross members 92 and 93 extending between side members 91 in front. The rear converging ends of side members 91 are joined by a plate member as indicated at 94, and a bracket 95 is also arranged at this point to carry a swivel mounted

roller 96. Similar brackets 97 are arranged at the front ends of side members 94 to provide mountings for front rollers 98. By this arrangement the supporting frame structure is adapted for presenting the core taking tube 90 easily to an opposed supported bale in order to take a sample.

The supporting frame structure further comprises upstanding support arms which are inclined inwardly, two of which are arranged forwardly as at 99 and 100, and a third is positioned to extend from the rear plate member 94 as at 101. The upper extending ends of these support arms 99, 100, and 101, are disposed for supporting attachment to a bracket member indicated at 102 in Fig. 6. The bracket member 102 is formed with a bottom portion adapted as at 103 to support a motor drive 104, and with bearing standards 105 and 106 in which bearing mountings 107 and 108 for supporting the core taking tube 90 are provided, as described more in detail below.

The arrangement for supporting the core taking tube 90 is shown best in Figs. 10 and 11, and comprises a sleeve 109 which is freely rotatable in bearings 107 and 108 but is retained against endwise movement by collars 110 fixed in place as by set screws 111. A pulley member 112 is keyed on sleeve 109 between bearing mountings 107 and 108 as at 113, and this pulley member 112 is driven through a suitable connection, such as belt 114, from motor drive 104. The motor drive 104 may consist of an electric motor as illustrated, the connections for the motor being shown at 115 running to a switch control 116 beyond which a conventional extension is arranged, as indicated at 117, for connection to any convenient power source (not shown). The switch control 116 is positioned in easy reach on an upright 118 which may be steadied by a brace as at 119.

The sleeve 109 is further arranged with an internal diameter adapted to receive the core taking tube 90 as shown in Figs. 10 and 11. At the forward end of sleeve 109 notches 120 are provided to engage interfitting lugs 121 formed in a flange 122 on core taking tube 90. This notch and lug arrangement provides a fixed clutch connection between core taking tube 90 and sleeve 109 which is adapted for easy assembly and removal of core taking tube 90. As sleeve 109 is driven through pulley 112 and belt 114 from motor 104, the core taking tube 90 will be rotated with sleeve 109, by virtue of the fixed clutch connection just described, for operation as a sample is taken.

The extending end of core taking tube 90 is provided, as before, with a cutting tip 123 which as previously mentioned may be formed of material having appropriate cutting characteristics and welded in place as at 124. When presented to a bale to be sampled this cutting tip 123 will penetrate the bale and effect taking of a sample which will be received in core taking tube 90 as the penetration progresses. The disposition of the supporting frame structure is such that the core taking tube 90 and associated cutting tip 123 may be easily presented for this operation in relation to an opposed supported bale. The frame structure may be further adapted for this purpose by arranging a manipulating handle as at 125 through which positioning of the frame structure may be conveniently controlled and the necessary pressure for the core taking operation advantageously exerted.

The type of sample obtained with my device is illustrated in Fig. 12, and it will be understood

that this sample will be contained in the core taking tube after removal from the bale being sampled. The arrangement of the ejecting means for removing this sample from the core taking tube in the first embodiment of my invention described above has already been noted. In the presently described modified form of my invention, the ejecting means takes the form of a rod member 126 having a handle portion 127. The rod member 126 is formed in a diameter such as will allow it to fit snugly but easily movable in the core taking tube 90 (see Fig. 10). Ejector rod 126 may accordingly be associated with core taking tube 90 as illustrated in Fig. 10, with the handle portion 127 extending to the rear as shown in Fig. 6, for example. In this position, the relative disposition of handle portion 127 and frame structure handle 125 will prevent ejector rod 126 from rotating with core taking tube 90 during the sample taking operation.

After the sample has been taken into the tube 90 as described above, and the frame structure has been manipulated to remove tube 90 from the sampled bale, the ejector rod 126 may then be advanced in tube 90 to recover the sample for investigation. For this purpose, ejector rod 126 extends in excess of the length of core taking tube 90 so that complete ejection can be effected, and handle portion 127 provides a convenient means for obtaining the necessary leverage on rod 126 to force the ejection.

The application of this modified form of my invention in commercial operations is illustrated in Figs. 13 and 14. Bales of fibrous material, such as bast fiber, are indicated at 128 on a skid 129 as they might be arranged for storage at a paper mill, for example. In order to determine the average physical and chemical characteristics of these bales it is necessary, as mentioned above, to take representative samples for investigation. The presently described modified form of my invention is readily adapted for this purpose without requiring any disarrangement of the bales as prepared for storage, as indicated above. The sampling device may be presented to the bales 128 as they stand on the skid 129 (see Fig. 14) to take samples from a representative number of the bales.

The position assumed by the core taking tube 90 during the sample taking operation is illustrated in Fig. 13. As shown, the core taking tube 90 is presented lengthwise of the bale to take full advantage of the depth of penetration possible by virtue of the arrangement according to the present invention. The sample taking operation may be performed easily and rapidly in this manner, and may in fact be carried out in connection with transfer of the bales to storage after they have been unloaded and arranged on the skids 129.

In either of the illustrated embodiments of my sampling device, it will be noted that the bale sampler is provided with a supporting member or frame structure forming a stable and independent support relative to a bale to be sampled so that relatively great pressure may be exerted to cut and remove a sample from the bale; and that associated ejecting means are arranged to recover the sample taken from the bale for investigation. It will accordingly be apparent that the structural details of my sampling device as described above may be modified and changed within the scope of the appended claims, and that the present invention is not limited to the specific

constructions described above and illustrated in the accompanying drawing.

I claim:

1. In a bale sampler and the like, a wheeled supporting base, means for positioning and clamping a bale or other compact mass of material to hold the same on the base, an open-ended, interiorly unobstructed, vertically moveable, motor-driven, rotatable core-taking tube located vertically above the bale or mass supporting area of the base, the tube having an annular, forward, cutting end, to penetrate the underlying positioned material and take a core of the material into the tube, manually operable means for raising and lowering said core-taking tube at will, and manually operable ejector means for removing the entire core of material taken into the tube, said ejector means comprising an elongated, vertical rod of excess length and approximate tube-bore diameter, cooperatively positioned normally above and in axial alignment with and enterable endwise and movable lengthwise in said core-taking tube, an inverted, substantially U-shape operator element rigidly secured at its middle to the upper end of said ejector rod, with the legs of said operator element depending in spaced, parallel relation on opposite sides of said rod and having hand grasp portions at their lower ends for the downward and upward manipulative actuation of the rod, and means for releasably holding said ejector rod in its raised, normally inactive position.

2. In a bale sampler, a wheeled supporting base, an open-ended, interiorly unobstructed, motor-driven, rotatable core-taking tube mounted on the base, the core-taking tube having an annular, forward, cutting end adapted to penetrate a bale or other compact mass of material and take a core of the material into the tube, manually operable means for forcing the core-taking tube into and withdrawing it from the material at will, and manually operable ejector means for removing the entire core of material taken into the core-taking tube, said ejector means comprising an elongated rod of excess length and approximate tube-bore diameter, cooperatively positioned in axial alignment with and enterable endwise and movable lengthwise in said core-taking tube, an inverted, substantially U-shape operator element rigidly secured at its middle to the rear end of said ejector rod, with the legs of said operator element extending in spaced, parallel relation on opposite sides of said rod and having hand grasp portions at their forward ends for manipulative actuation of the rod, and means for releasably holding said ejector rod in normally inactive position.

3. A bale sampler supported independently of the bale to be sampled and adapted to exert relatively great pressure against a bale of compact fibrous material to cut and remove a cylindrically shaped sample therefrom, comprising a wheeled supporting member forming a stable and independent support on a floor or like surface relative to the material to be sampled, an elongated, cylindrical, core-taking tube rotatably mounted on said supporting member and extending in core-taking length beyond its mounting on said supporting member, said tube being open at its opposite ends, being formed with a bore of uniform diameter whereby said tube is interiorly unobstructed throughout its entire length, and having a forward cutting end adapted to penetrate an opposed supported bale of fibrous material and take into the tube a core of the material as

the same is cut, cooperatively associated power means for rotating said core-taking tube, means for guiding said core-taking tube when said tube is forced endwise into the opposed bale and for withdrawing the tube from the bale, a cooperatively associated ejector rod of substantial length and approximate tube-bore diameter, and means for detachably supporting said ejector rod on said supporting member in axial alignment with the core-taking tube to facilitate manual entry thereof endwise into and movement lengthwise through said core-taking tube to eject from the tube for further use the fibrous sample taken from the bale.

15 4. A bale sampler adapted to exert relatively great pressure against a compact bale of fibrous material to cut and remove a sample therefrom, comprising a supporting member forming a stable and independent support on a floor relative to the fibrous bale to be sampled, an elongated, cylindrical, core-taking tube rotatably mounted on said supporting member, said tube being formed with a bore of uniform diameter whereby it is interiorly unobstructed throughout its entire length and having a forward cutting end adapted to penetrate an opposed supported bale of fibrous material and take into the tube a core of the material as the same is cut, means for rotating said core-taking tube, an ejector rod of approximately tube-bore diameter cooperatively associated with said tube, and means for detachably supporting said ejector rod on said supporting member in axial alignment with said tube to facilitate manual entry thereof endwise into and movement lengthwise through said tube after the tube has cut the sample and has been removed from the bale to eject from the tube for investigation the fibrous sample taken from the bale.

5. A bale sampler supported independently of a bale to be sampled and adapted to be moved and brought into opposing position to the bale and to exert relatively great pressure against the bale to cut and remove a sample therefrom, comprising a supporting member adapted to be disposed on a floor relative to the bale to be sampled, an elongated, cylindrical, core-taking tube rotatably mounted and horizontally disposed on said supporting member, said tube being formed with a bore of uniform diameter whereby it is interiorly unobstructed throughout its entire length and having a forward cutting end adapted to penetrate an opposed supported bale to be sampled and take into the tube a core of the material as the same is cut, means for rotating said core-taking tube, an ejector rod of approximate tube-bore diameter cooperatively associated with said tube, and means for detachably supporting said ejector rod on said supporting member in axial alignment with said tube to facilitate manual entry thereof endwise into and movement lengthwise through said tube after the tube has cut the sample and has been removed from the bale to eject from the tube for investigation the fibrous sample taken from the bale.

6. A bale sampler adapted to be brought into opposing position to a bale to be sampled and to exert relatively great pressure against the bale to cut and remove a sample therefrom, comprising a supporting member forming a stable and independent support on a floor relative to the bale to be sampled, a cylindrical core-taking tube rotatably mounted on said supporting member, said tube being formed with a uniform bore whereby it is interiorly unobstructed throughout its entire length and having a forward cutting end adapted

to penetrate an opposed bale and take into the tube a sample core from the bale as the same is cut, means for rotating said core-taking tube, and an ejector rod of approximately tube-bore diameter cooperatively associated with said core-taking tube and supported on said supporting member in axial alignment with said core-taking tube, said ejector rod being adapted for manual entry endwise into the tube after a core has been cut and removed from the bale to eject from the tube for investigation the sample core taken from the bale.

ROBERT M. LEVY.
